**REMOVABLE CORNER STRUCTURE
FOR SHELVING**

Louis Maslow, Dallas, Pa., assignor to Metropolitan
Wire Goods Corporation, Wilkes-Barre, Pa.

Filed Oct. 24, 1973, Ser. No. 409,255

Term of patent 14 years

Int. Cl. D8—08

U.S. Cl. D8—236

FIG. 1.

FIG. 2.

FIG. 4.

FIG. 3.

FIG. 5.

FIG. 1 is a top plan view of a removable corner structure for shelving showing my new design;

FIG. 2 is a rear elevational view thereof;

FIG. 3 is a bottom plan view thereof;

FIG. 4 is an elevational view of one side thereof; and

FIG. 5 is an elevational view of another side thereof.

The hole shown in FIGS. 1 and 3 has straight tapering walls from top to bottom.

I claim:

The ornamental design for a removable corner structure for shelving, substantially as shown and described.
